JOHN J. REDMOND, OF TORONTO, ONTARIO, CANADA

PAPER CREEASING AND CUTTING APPARATUS

Application filed October 5, 1931. Serial No. 566,966.

This invention relates to apparatus for creasing and cutting off lengths of paper from a supply roll for use on cylindrical platens of printing presses. These platens 5 are each provided with a radially directed surface on which one end of the length of paper is secured, the remainder of the paper being curved round the cylindrical surface of the platen. This necessitates the paper 10 being creased to snugly fit the corner between the radial and curved surfaces of the platen and the object of this invention is to provide simple apparatus for producing the desired sheet of paper ready for application to the 15 platen without waste of time or material and without musing or damaging the latter.

I attain my object by providing a frame having bearings formed therein for supporting a roll of paper. The lead end of this 20 paper is fed by feed rollers over a bar which is provided with a straight-edge. A creaser comprising a roller having a V shaped groove adapted to co-operate with the straight-edge to form a transverse crease in the paper is 25 carried on a slide which is mounted on a guide carried by the bar. A second slide carrying a knife is also mounted on the guide for cutting the paper into measured lengths.

The constructions are hereinafter more 30 fully described and are illustrated in the accompanying drawing in which

Fig. 1 is a front elevation of my apparatus;

Fig. 2 a plan view thereof;

Fig. 3 an end view thereof; and

Fig. 4 a cross sectional detail.

In the drawing like numerals of reference indicate corresponding parts in the different figures.

40 1 is a frame comprising two side members 1^a in which are formed bearings 2 for supporting a roll of paper 3. The lead end of the paper 3 is passed between a set of feed rollers 4 and 5 which feed the paper over a bar 6 extending across the front of the frame and secured to the forward edges of the side members 1^a. On the bar is carried a guide 7 on which is mounted a creaser comprising a slide 8 mounted on the guide and a roller 9 journaled on the slide. The roller is provided

with a V shaped groove adapted to co-operate with a straight-edge 10 formed on the bar 6 to form a transverse crease in the paper.

Any suitable well known measuring instrument such as a yardstick 11 may be used to 55 measure the paper and, when the desired length has been fed by the feed rollers 4 and 5 past a stationary shear blade 12, a knife 13 is adapted to cut this length from the web wound on the supply roll. A rotary knife is 60 employed which is journalled on a second slide 14 mounted on the guide 7 and is adapted to co-operate with the stationary shear blade 12 which is located behind the bar 6.

In practice the rollers 4 and 5 are turned 65 by a crank 15 to feed a few inches of paper past the straight-edge 10, the operator then manually bends the paper over the straight-edge and then runs the grooved roller over the partial crease in the paper which results 70 in a straight and permanent crease being formed therein. The feed rollers are again turned and, when the desired length of paper has been unwound from the supply roll, the knife is then operated to cut off this length. 75 By returning the slides 8 and 14 to their normal positions at opposite ends of the guide 7, either slide may be operated independently of the other.

What I claim as my invention is:

1. Paper cutting apparatus comprising a 80 frame having bearings for supporting a roll of paper; a bar supported on the frame parallel to the axis of the bearings, the bar being provided with a straight-edge on which the paper may be creased; a guide supported in spaced relationship to the bar; and means carried by the guide for co-operation with the straight-edge to crease the paper.

2. Paper cutting apparatus comprising a 85 frame having bearings for supporting a roll of paper; a bar supported on the frame parallel to the axis of the bearings, the bar being provided with a straight-edge on which the paper may be creased; a guide supported in spaced relationship to the bar; a slide mounted on the guide; a creasing element carried by the slide and co-operating with said straight-edge; a knife carried by the slide; and a shear 90

blade, complementary to the knife, located behind the said straight-edge.

3. Paper cutting apparatus comprising a frame having bearings for supporting a roll of paper; a bar supported on the frame parallel to the axis of the bearings, the bar being provided with a straight-edge on which the paper may be creased; a guide supported in spaced relationship to the bar; a knife slidably mounted on the guide; a creaser comprising a slide mounted on the guide; and a roller having a V shaped groove adapted to co-operate with the straight-edge to crease the paper thereon.
- 15 4. Paper cutting apparatus comprising a frame having bearings for supporting a roll of paper; a bar supported on the frame parallel to the axis of the bearings, the bar being provided with a straight-edge; means for feeding the lead end of the roll of paper across the straight-edge; a guide carried by the bar in spaced relationship thereto; a knife slidably mounted on the guide; and a creaser comprising a slide mounted on the guide, and a roller having a V shaped groove adapted to co-operate with the straight-edge to crease the paper thereon.
- 20 5. Paper cutting apparatus comprising a frame having bearings for supporting a roll of paper; a bar supported on the frame parallel to the axis of the bearings, the bar being provided with a straight-edge; means for feeding the lead end of the roll of paper across the straight-edge; a guide carried by the bar in spaced relationship thereto; a knife slidably mounted on the guide; a shear blade complementary to the knife; and a creaser comprising a slide mounted on the guide, and a roller having a V shaped groove adapted to co-operate with the straight-edge to crease the paper thereon.
- 25 6. Paper cutting apparatus comprising a frame for supporting a roll of paper; a straight-edge carried by the frame parallel to the axis of the roll; a creaser adapted to co-operate with the straight-edge to crease the paper thereon; a knife; and a stationary shear blade complementary to the knife, located to one side of the straight-edge.
- 30 50 Signed at the city of Toronto, Canada, this 2nd day of October, 1931.

JOHN J. REDMOND.
